ABSTRACT: A fire box adjustor for a charcoal broiler wherein a plurality of struts are connected by swivels to a fire box support and to a lower pan. The fire box support is guided for vertical non-rotational movement. The pan is rotatably mounted in a housing. A rod having a handle is connected to the pan for rotating the pan. Rotation of the pan orients the struts to raise and lower the fire box.

FIRE BOX ADJUSTOR FOR CHARCOAL BROILER

BRIEF DESCRIPTION OF THE INVENTION

A housing has a circular opening in it for supporting a pan for rotational movement. The pan has flanges overlying the bottom wall of the housing beyond the periphery of the circular opening and has clamps for providing frictional restraints against rotational movement of the pan. A rod is connected to a side of the pan and the outer end of the rod has a handle to be grasped for swinging the rod to rotate the pan. A fire box for containing charcoal is positioned above the pan. A plurality of struts are connected to swivel brackets on the lower side of the fire box support and to swivel brackets on the upper surface of the bottom wall of the pan. The fire box support is guided for vertical and non-rotational movement so that, as the pan rotates, the fire box support is prevented from rotating. As the pan rotates, it rotates the brackets carried by it and therefore swings the struts to move them between generally horizontal positions to generally vertical positions. As the struts are thus moved, they raise and lower the fire box support.

BRIEF DESCRIPTION OF THE DRAWINGS

FIG. 1 is a top plan view of the fire box support and adjustor assembly.

FIG. 2 is a front elevation view of the fire box support and adjustor assembly.

FIG. 3 is a right side elevation view of the fire box support and adjustor assembly with portions shown in section.

FIG. 4 is a fragmentary rear elevation view of the fire box support and adjustor assembly.

FIG. 5 is an enlarged fragmentary view in section taken along the line 5—5 of FIG. 1.

FIG. 6 is a top plan view of the fire box support and adjustor assembly with portions shown in section and showing the fire box in a partially elevated position.

FIG. 7 is a front elevation view of the fire box support and adjustor assembly in the condition illustrated in FIG. 6.

FIG. 8 is an enlarged fragmentary view in section taken along the line 8—8 of FIG. 6.

FIG. 9 is a top plan view of the fire box support and adjustor assembly rotated to the fully elevated position.

FIG. 10 is a front elevation view of the fire box support and adjustor assembly in the condition of FIG. 9.

FIG. 11 is an enlarged fragmentary top plan view of the pan illustrating a brake clip and a strut and bracket.

FIG. 12 is a fragmentary view in section taken along the line 12—12 of FIG. 11.

FIG. 13 is a fragmentary view in section taken along the line 13—13 of FIG. 11.

FIG. 14 is a fragmentary view in section illustrating the upper portion of the strut of FIG. 13 and the upper swivel bracket.

DETAILED DESCRIPTION OF THE INVENTION

As shown in the drawings, the fire box adjustor for a charcoal broiler 20 has a lower housing 21 that comprises side panels 22 and 23 and a back panel 24, all joined to a bottom panel 25. There are upper flanges 26 and 27 joined to the upper edges of the side panels 22 and 23, and an upper flange 28 joined to the upper edge of the back panel 24. A front upper flange 29 is welded between the flanges 26 and 27. The space between the front flange 29 and the bottom panel 25 is open, and a door 30 having side flanges 31 and 32 is hinged on suitable pins or rivets 33 that extend through the lower corners of the side flanges 31 and 32 and through the side panels 22 and 23. The door 30 has a knob 34 by which it can be swung open to expose the open front for cleaning purposes and for sliding a fire box into the housing. The housing may be other than rectangular, or its construction may be varied. Also, the usual upper housing (not shown), enclosing a suitable cooking grill with a cover and a water pan as desired, would be mounted above the lower housing 21.

As shown in FIG. 1 and 4, an axle 37 extends through the lower rear corners of the side panels 22 and 23, and wheels 38 are mounted on the outer ends of the axle 37. A leg 39 is connected to the bottom panel 25 adjacent the front of the housing 21 and midway between the side panels 22 and 23. There is a rubber or plastic foot 40 on the lower end of the leg 39.

The bottom panel 25 has a circular opening 42 in it. A pan 43 has a cylindrical side wall 44 that projects downwardly through the opening 42 and has a bottom wall 45. An annular flange 46 joined to the upper edge of the cylindrical side wall 44 overlies the bottom panel 25 radially outwardly of the opening 42. There are a plurality of clips 47 acting as brakes positioned about the periphery of the annular flange 46 and fastened to the bottom panel 25 by bolts 48. As shown in FIGS. 11 and 12, the clips 47 have radially inwardly extending arms 49 that overlie and press against the annular flange 46. Thus, the annular flange 46 is pressed between the bottom panel 25 and the overlying arms 49 to restrain rotation of the pan 43 unless an external force is applied.

As shown particularly in FIGS. 1, 9 and 10, a rod 52 is welded to a plate 53 that is fastened by rivets 54 to the cylindrical side 44 of the pan 43. The rod 52 has a section 55 that, as viewed in FIG. 1, extends outwardly and is curved to the right, joining a section 56 that generally parallels a segment of the periphery of the pan 43. The section 56 leads to another section 57 that extends straight to the right past the right-hand wheel 38 and leads to an up-turned end 58 (see FIG. 2). A vertically upwardly extending handle 59 is connected to the upwardly extending end 58 of the rod 52.

A pair of vertical channel members 62 and 63 are positioned adjacent the centers of the inner surfaces of the side panels 22 and 23 respectively. As shown in FIG. 5, each channel member is connected to the housing 21 by an angle member 64 welded to it and fastened by rivets or screws 65 to the adjacent flanges 26 and 27, respectively, and by a lower tab 66 fastened to the bottom panel 25 by a rivet or screw 67. The channels 62 and 63 are oriented to present their vertical grooves 68 and 69, respectively, inwardly.

A rectangular fire box support 72 comprises a bottom panel 73 with side walls 74 and 75 and a back wall 76. There is no front wall, thereby facilitating sliding of a fire box (not shown) onto the support 72 after the charcoal has been lighted and properly conditioned remote from the broiler. There are narrow plates 77 and 78 welded to the underside of the bottom wall 73 of the fire box support 72 and received within the vertical grooves 68 and 69 of the channel members 62 and 63 respectively. The narrow plates 77 and 78 ride within the vertical grooves 68 and 69 to permit vertical movement of the fire box support 72 while preventing rotation.

There are three U-brackets 81, 82 and 83 each of which is swivelly connected by a rivet 84 to the bottom 45 of the pan 43. The U-brackets 81, 82 and 83 are equally spaced about the bottom 45 of the pan 43 and are positioned near the cylindrical side wall 44. Similarly, three U-brackets 85, 86 and 87 face downwardly and are pivotally connected to the bottom panel 73 of the fire box support 72 by rivets 88.

Three struts 90, 91 and 92 in the form of channel members 60 are connected between the pan 43 and the fire box support 72, the strut 90 being pivotally connected by a pin 93 that extends between the upstanding ears of the brackets 81 and pivotally connected by a pin 94 connected between the ears of the downwardly extending bracket 85 (see FIGS. 11 and 13), the strut 91 being pivotally connected by similar pins 93 and 94 that extend between the ears of the brackets 82 and 86 respectively, and the strut 92 being pivotally connected by similar pins 93 and 94 that extend between ears of the brackets 83 and 87 respectively.

OPERATION

A fire box having properly conditioned burning charcoal is slid onto the fire box support 72. This is conveniently done by opening the front door 30 and pushing the fire box (not

shown) onto the fire box panel 73 since there is no obstructing front panel on the fire box support 72. Above the housing 21 and above the vertical guides 62 and 63, the food to be cooked is placed upon a suitable grill (not shown). Through the mechanisms of this invention, the height of the fire box support 72 is adjustable between the low position illustrated in FIGS. 1 through 5 to the upper position illustrated in FIGS. 9 and 10.

In the low position, the handle 59 has been grasped to swing the rod 52 to the position illustrated in FIG. 1 until the portion 57 of the rod 52 has contacted the right-hand wheel 38. In this position, the pan 43 has been rotated to position the brackets 81, 82 and 83 in the location shown in FIG. 1. Since the fire box support 72 is prevented from rotating by the interengagement of the narrow plates 77 and 78 within the vertical grooves 68 and 69 of the guides 62 and 63, the brackets 85, 86 and 87 are always maintained in the relative positions illustrated in FIG. 1. When the brackets 81, 82 and 83 are swung to the position shown in FIG. 1, therefore, the struts 90, 91 and 92 extend diagonally and therefore draw the fire box support 72 down to the low position illustrated in FIG. 5.

To elevate the fire box support 72, the handle 66 is grasped to draw the rod 52 in a clockwise direction away from the right-hand wheel 38. The rod 52 may be turned to an intermediate position such as the one illustrated in FIG. 6. In this position, the rod 52 and the pan 43 have been rotated approximately 120°. This means that the brackets 81, 82 and 83 have been rotated approximately 120° from the positions they occupied as shown in FIG. 1. This moves the brackets 81, 82 and 83 to within approximately 60° arc spacing from their associated brackets 85, 86 and 87 respectively, moving the struts 90, 91 and 92 from diametric orientation part way toward vertical orientation. The swivel connections of the brackets 81, 82, 83, 85, 86 and 87 permit these motions to take place. Movement of the struts 90, 91 and 92 toward vertical positions forces the fire box support 72 to the intermediate elevated position illustrated in FIGS. 7 and 8. Movement of the rod 52 to any other intermediate position can be done to position the fire box support 72 to any other desired intermediate position.

To fully elevate the fire box support 72, the rod 52 is swung to the position illustrated in FIGS. 9 and 10. In this position the curved section 55 of the rod 52 contacts the leg 39, this contact acting as a limiting stop against further swinging movement of the rod 52. This further swinging movement of the rod 52 swings the pan 43 through a farther arc of approximately 60° beyond the position illustrated in FIG. 6 for a total rotation of approximately 180° from the position illustrated in FIG. 1. It swings the brackets 81, 82 and 83 to the relative positions illustrated in FIG. 9 at which they are almost directly below the brackets 85, 86 and 87 respectively. This forces the struts 90, 91 and 92 to approximately vertical positions and forces the fire box support 72 to its maximum height as illustrated in FIG. 10.

As the pan 43 is rotated by movement of the rod 52, the fire box support 72 is prevented from rotating as the narrow plates 77 and 78 are guided vertically within the vertical grooves 68 and 69 of the vertical channels 62 and 63. To lower the

fire box support 72, the rod 52 is simply moved in a reverse direction and this rotates the pan 43 in a counter clockwise direction to reverse the procedure already described. When the rod 52 is swung to the position shown in FIG. 1 with the rod section 57 contacting the wheel 38, further movement of the rod 52 in a counter clockwise direction is stopped and the fire box support 72 is again positioned in its lowest position.

The restraint to rotation of the pan 43 produced by the friction of the arms 49 overlying the annular flange 46 helps hold the pan 43 in any rotated position. Yet, because of the leverage provided by the rod 52, the pan 43 is freely rotatable when the rod is swung.

Various changes and modifications may be made within this invention as will be readily apparent to those skilled in the art. Such changes and modifications are within the scope and teaching of this invention as defined by the claims appended hereto.

I claim:

1. A fire box adjustor for a charcoal broiler comprising a housing for supporting charcoal broiler components, a pan rotatably supported adjacent the bottom of the housing, means to rotate the pan about a vertical axis, a fire box support for supporting charcoal, a plurality of struts, means to pivotally and swivelly connect one end of each strut to the fire box support and the other end of each strut to the pan, means to guide the fire box support for nonrotational vertical movement, and means to rotate the pan to move the fire box support vertically.
2. The fire box adjustor of claim 1 wherein the housing has a round opening in its bottom, the pan extending through the opening and having a flange overlying the bottom of the housing radially beyond the opening, and friction-producing means connected to the housing to frictionally restrain the pan against rotation.
3. The fire box adjustor of claim 1 including supports for supporting the housing on a horizontal surface, at least some of the supports comprising wheels, the means to rotate the pan comprising a rod having one end connected to a side of the pan and the other end having a handle on it, the rod being bent to substantially parallel a segment of the periphery of the pan.
4. The fire box adjustor of claim 3 wherein the rod has a portion adjacent the handle positioned to be stopped against one of the housing supports and a portion adjacent the said one end positioned to be stopped against another one of the housing supports to limit the swinging arc of the rod and thereby define the limits of the rotation of the pan.
5. The fire box adjustor of claim 1 wherein the means to guide the fire box support comprises a pair of vertical posts connected to diametrically opposite sides of the housing, a pair of lugs connected to diametrically opposite sides of the fire box support and the lugs and posts having a tongue and groove interfit.
6. The fire box adjustor of claim 4 wherein there are three housing supports, two of which are wheels and the third of which is a fixed leg.
7. The fire box adjustor of claim 3 wherein the handle extends vertically upwardly from the rod.
